CHILD'S WARDROBE

Domenick A. Caruso, Atlantic Highlands, N. J.

Application May 11, 1948, Serial No. 146,289

Term of patent 3½ years

(Cl. D33—8)

To all whom it may concern:

Be it known that I, Domenick A. Caruso, a citizen of the United States, residing at Atlantic Highlands, in the county of Monmouth and State of New Jersey, have invented a new, original, and ornamental Design for Child's Wardrobe, of which the following is a specification, reference being had to the accompanying drawing, forming a part thereof.

In the drawing:

Fig. 1 is a perspective view of a child's wardrobe embodying my new design;

Fig. 2 is a front elevational view of the same; and

Fig. 3 is a side elevational view of the same.

I claim:

The ornamental design for a child's wardrobe, as shown.

DOMENICK A. CARUSO.
